Producer Engineering—7/78—p. 83—Analyzer at left—center.

Primary Examiner—Nelson C. Holtje

[57] **CLAIM**

The ornamental design for an engine analyzer, as shown and described.

DESCRIPTION

The FIGURE is a left front perspective view of an engine analyzer showing our new design, the top, bottom and rear sides being flat, plain and unornamented, and the right side being a mirror image to the left. The broken-line base unit is environmental and forms no part of the claimed design.
